UNITED STATES PATENT OFFICE.

PETER J. HARLEMAN, OF BOSTON, MASSACHUSETTS.

MECHANICAL STOKER.

SPECIFICATION forming part of Letters Patent No. 727,940, dated May 12, 1903.

Application filed September 16, 1901. Serial No. 75,643. (No model.)

To all whom it may concern:

Be it known that I, PETER J. HARLEMAN, of Boston, in the county of Suffolk and State of Massachusetts, have invented certain new and useful Improvements in Mechanical Stokers, of which the following is a specification.

My invention relates to new and useful improvements in mechanical stokers; and its object is to, first, obtain the greatest number of heat units by facilitating the combustion of the fuel; second, to adjust the grate to different positions best adapted for different grades of fuel, and, lastly, to prolong the life of the grate.

My invention consists of certain novel features hereinafter described, and particularly pointed out in the claims.

In the accompanying drawings, which illustrate a construction embodying my invention, Figure 1 is a front view of a furnace with parts in section. Fig. 2 is a side view of the furnace and grate with one of the side walls removed. Fig. 3 is a sectional view through the grate. Fig. 4 is a view looking from the lower end of the grate with parts in section to illustrate construction. Fig. 5 is a detail sectional view on the line XI XI, Fig. 7. Fig. 6 is a detail view of one end of the grate-bar, showing the ratchet. Fig. 7 is a side view of one of the grate-bars, partly broken away to show the interior arrangement. Fig. 8 is a detailed sectional view of certain mechanism for causing the rotation of the grate-bars. Fig. 9 is a detail side view of a modified grate-bar. Fig. 10 is an end view of one of the sections of the grate-bar shown in Fig. 9.

Like letters of reference refer to like parts throughout the several views.

Within the side walls A and resting upon the front wall B and rear wall C is a water-tube boiler D, and below said boiler is a grate E, consisting of a number of hollow tubes F, each provided on one end with a ratchet G. A number of pawls J are pivoted on the lever H and weighted to cause their engagement with the ratchets G on each of the grate-bars. Each of these grate-bars F rests upon transverse pairs of rollers M⁴, mounted in the upper end of the standards M³, secured by suitable bolts to the angle-irons M M' M². (See Fig. 4.) The opposite angle-irons M M'

are connected together by the cross-irons M⁵ and M⁷, which are bolted at each end to the said angle-irons, and the middle iron M' is secured to said cross-irons M⁵ and M⁷, by means of which all three of the angle-irons are held firmly in position. The angle-irons M and M² are pivoted at M⁶ on the standards A² and A³, resting on the base A', so that said grate E can be adjusted to any position, as indicated in dotted lines, for different grades of coal. The lever H is pivoted to the link K¹², which in turn is pivoted on the angle-iron M at K', and its opposite end is pivoted at K² to the link K¹⁰, and between the links K¹⁰ and K¹² is pivoted the lever K¹¹ at K², and said link K¹⁰ is pivoted at K³ in a depending lug on the angle-iron M, and to the lower end of the link K¹⁰ is pivoted at K⁴ the lever K⁵. (See Figs. 1, 2, and 8.) The lever K¹¹ extends forwardly and is pivoted to the link H', which is suitably pivoted at H² in the front wall and at its upper end to the lever H, so that these levers when operated move in opposite directions. This lever K⁵ extends forwardly and is pivoted at K⁶ to the bell-crank lever K⁷, to which is connected at K⁸ the lower end of the rod K⁹, operated by an eccentric L, driven by the shaft L', on which is mounted a fast and a loose pulley L² and L³, with the fast one of which the belt L⁴ is adapted to engage and operate the rod K⁹.

The arrangement of the lever H, links K¹⁰ and K¹², and lever K¹¹, as previously described in detail, distributes the strain produced by the motion of the lever K⁵ and creates a tension on these elements to keep the grate in proper working order and at the same time avoids compression, which would occur if the lever K¹¹ were omitted.

In the operation of the rod K⁹ when the lever K⁵ is pulled forwardly the lever K¹¹ moves rearwardly and the lever H forwardly, so that the pawls J, engaging the ratchets G, turn the grate-bars F, and in the rearward movement of the lever K⁵ the lever K¹¹ moves forwardly and the lever H rearwardly, so that the pawls J are brought back into position to engage another tooth on the ratchets G of the grate-bars F, and this operation is continued, so as to keep the grate-bars intermittently revolving, whereby the life of the grate-bars is prolonged, as no one part is subject to a greater

heat than another, each part of the surface of the grate-bars being brought from time to time to the top, and the part removed from contact with the fuel is cooled by the air 5 passing through the grate-bars, and the air being heated by contact with the grate-bars facilitates the combustion of the fuel.

Opposite the end of each grate-bar is an opening A⁴, which is closed by the cap A⁵, and through said opening steam may be passed in order to clean out the grate-bars, or, if desired, air can be admitted through said openings; but ordinarily the air is admitted through the front doors and passes up into the 10 grate-bars through the lower openings and out through the upper openings, thereby cooling the lower portions of the grate-bars, and is heated to facilitate combustion.

Located on the bottom of each grate and 15 pivoted at N' on the angle-irons M M' M² there are located four dumping-grates N of the usual construction, having a rear plate N⁹, and each dumping-grate is pivoted at N² to a lever N³, which is normally held in the 20 position shown in full lines, Fig. 3, by the latch N⁸. When it is desired to dump these grates to remove the ashes and clinkers, the fireman, opening the doors and taking hold of the handles N', located opposite each door, 25 can operate one or more of these levers in succession and move the same to the position shown in dotted lines, Fig. 3, so that the ashes and clinkers will be dumped to the bottom of the furnace. To the lever N³ is pivotally connected at N⁵ the arm N⁴, which is pivoted on a stud N⁶, extending down from the angle-iron M', as shown in Fig. 3.

It is desirable to change the location of the grate for different grades of coal, and for this 30 purpose I have provided means for moving the front end of the grate-bar up and down, as shown in the full lines and dotted lines, Figs. 2 and 3, and to this end have connected chains O' to the lugs O, (see dotted lines, Fig. 45 1,) and the upper ends of the chains pass around the drums O² on the shaft O³, and on one end of the shaft beyond the drum is the gear-wheel O⁴, with which works the worm-gear O⁵, and by operating the handle O⁶ the 50 location of the grate-bars F of the grate E can be varied.

The coal or fuel is placed in the hopper P, and the amount passing from the hopper onto the grate is controlled by the gate P', which 55 on one side is provided with lugs P², (see dotted lines, Fig. 3,) located around the screw-threaded shafts P³, which at their lower ends have a bearing P⁵, one of which is shown in dotted lines, Fig. 1, and the upper end of 60 each of said screw-threaded shafts is provided with a bevel-gear P⁶, Fig. 1, with each of which is adapted to engage a bevel-gear P⁷, fast on the shaft P⁸, mounted in suitable supports, and on one end of said shaft is 65 located a bevel-gear P⁹, with which is adapted to engage another bevel-gear P¹⁰, and by operating the handle Q the position of the

gate P' can be varied with respect to the amount of opening between the hopper and the grate. In the lower end of the hopper is 70 located the feed-wheel R, mounted on a shaft R', journaled in the lower opposite sides of the hopper. This feed-wheel R is operated by the rod R⁶, secured at R⁷ to the rod K⁹, and connected to the said lower end of the said rod R⁶ is the lever R⁴, carrying the pawl R³, which is held inwardly by a spring R⁵ and adapted to engage with the teeth of the ratchet R² on one end of the shaft R' outside the hopper. 75

Within each grate-bar F is located a tumbler T, having three ears U, two of which are adapted to engage with the adjacent openings S of the lower part of the grate-bar, and the object of this tumbler is to provide means for 80 forcing out from the openings S cinders or ashes which may clog therein, so that as the grate-bars turn the tumbler falls by gravity into the next two adjacent openings, and this operation continues as the grate revolves, the 85 tumbler turning and occupying two of the openings at a time, as shown in Fig. 5.

The front of the furnace has the usual wall B', provided with the usual doors B².

Referring to Figs. 9 and 10, which illustrate a modification, a number of ring-sections F' are arranged together, and through said sections pass the rods F², on which the ring-sections are strung. Each section is provided with a number of shoulders F⁴, having lugs F³, which fit into recesses F⁵ in the corresponding lugs of the ring-sections adjacent. The spaces S' between the ring-sections allow the movement of air through the grate E'. Located in the bottom of the grate within the ring-sections is a tumbler T', having three ears U', which operate to clean out the spaces S' between the ring-sections F' in the rotation of the grate. 105

I do not limit myself to the arrangement 110 and construction shown, as the same may be varied without departing from the spirit of my invention.

Having thus described the nature of my invention and set forth a construction embodying the same, what I claim as new, and desire to secure by Letters Patent of the United States, is—

1. In an apparatus of the character described, a grate consisting of a series of hollow perforated grate-bars, mechanism for rotating said grate-bars, and a device having ears which are adapted to pass into the perforations of the grate-bars and thereby prevent clogging of the same. 120

2. In an apparatus of the character described, a grate consisting of a series of hollow perforated grate-bars, mechanism for rotating said grate-bars, and a device operated by gravity and having ears which are adapted 130 to pass into the perforations of the grate-bars and thereby prevent clogging of the same.

3. In an apparatus of the character described, a grate consisting of a series of hol-

low perforated grate-bars, mechanism for rotating said grate-bars, and a device in each of said grate-bars and having ears which are adapted to pass into the perforations of the grate-bars and thereby prevent clogging of the same.

4. In an apparatus of the character described, a grate consisting of a series of hollow perforated grate-bars, mechanism for rotating said grate-bars, and a device in each of said grate-bars operated by gravity and having ears which are adapted to pass into the perforations of the grate-bars and thereby prevent clogging of the same.

15 5. In an apparatus of the character described, a grate consisting of a series of hollow grate-bars, a ratchet on each grate-bar, a series of weighted pawls adapted to engage with said ratchets, a lever to which said pawls are pivoted for operating said pawls to move the grate-bars and to return said pawls to engage another tooth of the ratchets for the next movement of the grate-bars, another lever connected to the lever carrying the weighted pawls, links at both ends pivoted on an angle-iron to which said levers are pivoted, a third lever for operating said levers, a link pivoted on an angle-iron and connecting said third lever with the other two levers, a bell-crank pivoted to said last lever, and automatic mechanism for operating said bell-crank to produce a reciprocating motion of the grate-bar carrying the weighted pawls.

35 6. In an apparatus of the character described, a grate consisting of a series of hollow perforated grate-bars, a ratchet on each grate-bar, a series of weighted pawls adapted to engage with said ratchets, a lever to which said pawls are pivoted for operating said pawls to move the grate-bars and to return said pawls to engage another tooth of the

ratchets for the next movement of the grate-bars, another lever connected to the lever carrying the weighted pawls, links at both ends pivoted on an angle-iron to which said levers are pivoted, a third lever for operating said levers, a link pivoted on an angle-iron and connecting said third lever with the other two levers, a bell-crank pivoted to said last lever, and automatic mechanism for operating said bell-crank to produce a reciprocating motion of the grate-bar carrying the weighted pawls.

7. In an apparatus of the character described, a grate consisting of a series of hollow grate-bars, a ratchet on each grate-bar, rollers for supporting said grate-bars, supports in which said rollers are mounted, a series of weighted pawls adapted to engage with said ratchets, a lever to which said pawls are pivoted for operating said pawls to move the grate-bars and to return said pawl to engage another tooth of the ratchets for the next movement of the grate-bars, another lever connected to the lever carrying the weighted pawls, links at both ends pivoted on an angle-iron to which said levers are pivoted, a third lever for operating said levers, a link pivoted on an angle-iron and connecting said third lever with the other two levers, a bell-crank pivoted to said last lever, and automatic mechanism for operating said bell-crank to produce a reciprocating motion of the grate-bar carrying the weighted pawls.

In testimony whereof I have signed my name to this specification, in the presence of two subscribing witnesses, this 28th day of August, A. D. 1901.

PETER J. HARLEMAN.
